UNITED STATES PATENT OFFICE

171,013

MOTOR-TRANSMISSION UNIT

Daniel M. Schwartz, Salt Lake City, Utah, assignor to The Eimco Corporation, Salt Lake City, Utah, a corporation of Utah

Application February 4, 1953, Serial No. 23,449

Term of patent 14 years

(Cl. D77—1)

To all whom it may concern:

Be it known that I, Daniel M. Schwartz, a citizen of the United States of America, residing at Salt Lake City, county of Salt Lake, State of Utah, have invented a new, original, and ornamental Design for a Motor-Transmission Unit, of which the following is a specification, reference being had to the accompanying drawing forming a part thereof.

In the drawing:

Fig. 1 is a rear end elevational view of a motor-transmission unit showing my new design;

Fig. 2 is a top plan view of the same;

Fig. 3 is a left side elevational view of the motor-transmission unit shown in Fig. 1;

Fig. 4 is a front end elevational view of the same; and

Fig. 5 is a right side elevational view of the same.

I claim:

The ornamental design for a motor-transmission unit, substantially as shown.

DANIEL M. SCHWARTZ.
